CLAIM

The ornamental design for a children's play table, as shown and described.

DESCRIPTION

FIG. 1 is a first perspective view of a children's play table according to the design.

FIG. 2 is a second perspective view of the children's play table of FIG. 1.

FIG. 3 is a first side view of the children's play table of FIG. 1.

FIG. 4 is a second side view of the children's play table of FIG. 1.

FIG. 5 is an end view of the children's play table of FIG. 1, the opposite end view being substantially a mirror image thereof.

FIG. 6 is a top view of the children's play table of FIG. 1.

FIG. 7 is a bottom view of the children's play table of FIG. 1.

The broken lines in the drawings depict portions of the article that form no part of the claimed design.
